UNITED STATES PATENT OFFICE.

HENRY A. REGEN, OF BRECKENRIDGE, COLORADO.

COMBINED TOOL AND CLAMP.

Application filed April 22, 1925. Serial No. 25,015.

To all whom it may concern:

Be it known that I, HENRY A. REGEN, a citizen of the United States, residing at Breckenridge, in the county of Summit and State of Colorado, have invented certain new and useful Improvements in Combined Tools and Clamps; and I do declare the following to be a full, clear, and exact description of the invention, such as will enable others skilled in the art to which it appertains to make and use the same, reference being had to the accompanying drawings, and to the characters of reference marked thereon, which form a part of this application.

This invention relates to improvements in combined tools and clamps.

It is the object of this invention to produce an apparatus that shall be well adapted for several different uses and which shall be of simple and substantial construction.

My improved tool and clamp, briefly described, comprises two jaw members that are provided intermediate their ends with notches whose sides have spiral square cut threads which are adapted to cooperate with similar threads on opposite sides of a ring-like member which I shall hereinafter refer to as the nut. The jaws, when assembled in the hereinafter described relation with the nut, can be moved towards or away from each other with a parallel motion.

This invention can be most clearly described and will be most readily understood when reference is had to the accompanying drawing in which it has been illustrated and in which:

Fig. 1 shows a side elevation of one embodiment of my invention;

Fig. 2 is an end elevation looking in the direction of the arrow 2 in Fig. 1;

Fig. 3 is a section taken on line 3—3 Fig. 2;

Fig. 4 is a section taken on line 4—4 Fig. 3;

Fig. 5 is a side elevation, with parts broken away, of a modified form of my invention, and

Fig. 6 is a view, partly in elevation and partly in section, of a slightly different embodiment.

My invention comprises four parts which I have designated by numerals as follows: Numeral 1 designates the nut; 2 and 3 the movable jaw and 4 a removable portion of one of the jaws. The nut has parallel sides,

each of which is provided with a spiral thread 5 which are exactly alike on both sides and arranged in the same relation, by which I mean that in any diametrical section such as that shown in Fig. 3, the corresponding threads on opposite sides are exactly the same distance from the center. Jaw member 2 has a transverse notch 6 whose sides are provided with grooves 7 that are adapted to receive the threads 5. Jaw member 2 is so dimensioned that it can be threaded through the opening in the nut which, in this manner, is placed into operative relation with the sides of the notch 6 and by rotating the nut the cooperating threads on the nut and jaw will engage and the nut can be moved inwardly until it bottoms in the notch 6. The jaw member 3 is a duplicate of jaw member 2, except for this, that I make this member in two parts so that it can be inserted through the hole in the nut, after it has been inserted through the nut it is moved outwardly until the bottom of the notch 6 abuts the inside of the hole in the nut. The removable piece 4 is then put into place and fastened by means of screws 8 and 9. From Fig. 4 it will be seen that the jaw 3 has a slot 10 for the reception of the tongue 11 of member 4. This prevents relative rotation and produces a very solid and substantial construction. In order that the jaws shall be kept in alignment, I have provided each with a pair of fingers 12 that engage the sides of the other jaw. It will now be apparent that when the nut 1 is rotated with respect to the jaws, the latter will be moved away from or towards each other by a parallel motion in a manner analogous to that by which the jaws of an ordinary lathe chuck are moved. By providing the jaws with notches 6 within which the nut 1 is located, any force tending to bend the ends of the jaws apart will be resisted by the material of the nut with the result that the clamp is very rigid and strong. The ends of the jaws may be constructed in various ways so as to adapt them for various uses. I have shown the jaws provided with transverse notches by means of which a round member may be clamped or a square nut grasped and turned. The end of the jaws have been shown as provided with V-shaped grooves 14 in which a round or square member may be clamped. The remaining portions of the adjacent surfaces may be flat and smooth or roughened

in any way that may be best suited for the work that it is to do. In Fig. 5 I have shown a modification in which both of the jaws are identical and constructed like that indicated by numeral 2 in Figs. 1 to 3. As the removable part 4 has been omitted in this construction, it becomes impossible to assemble the parts if a nut made of a single piece is used. The nut has therefore been made in two parts which I have indicated as 1^A and 1^B. These parts are held in assembled relation by the screws 15. My device when constructed in the manner shown in Fig. 5 is more easily assembled than when constructed in the manner shown and described in Figs. 1 to 3.

In Fig. 6 I have shown a lock nut constructed in accordance with this invention. Instead of having jaws like those shown in Figs. 1 to 5, the jaws employed are similar but of somewhat different shape, the jaw marked 2^A corresponds to jaw 2 in Fig. 3 and jaw 3^A corresponds to jaw 3, while the removable part 4^A corresponds to member 4 in Fig. 3. One end of the jaws 2^A and 3^A has flat sides which cooperate to form a square portion 16 that can be engaged by a wrench. The adjacent surfaces are curved and threaded so as to engage the bolt 17. After the nut has been tightened it is clamped against the sides of the bolt by means of the clamping action of the nut 1. This nut or clamp may be employed as a connector for wires or other members.

In the above illustrations I have merely endeavored to describe the construction and show some of the uses to which the device may be put. I desire to call attention to the fact that this device may be employed for a large variety of uses and that the shape of the jaw member can be varied as may be required to make them adapted to perform the particular function that they are to perform. My invention in its broadest aspect relates to the use of a nut having its opposite surfaces provided with spiral threads that engage similar threads on the end walls of the notches in the jaws. This is an altogether different combination than that which is found in lathe chucks where the rotatable disk has spiral threads on one side

only. By having the opposite surfaces of the nut provided with spiral threads a parallel motion is obtained and the nut serves to strengthen the jaws.

Having now described my invention, what I claim as new is:

1. In a device of the class described, in combination, a pair of aligned jaw members adapted to be moved towards or away from each other, said jaws having each a notch with parallel opposed surfaces provided with spiral threads and a nut having its opposite sides provided with spiral threads adapted to engage the spiral threads in the walls of said notches whereby when the nut is rotated with respect to the jaws, the latter will move towards or away from each other with a parallel movement, one of said jaw members having a removable portion, one end of which forms one of the opposing surfaces of the notch.

2. A clamping device comprising, in combination, two opposed jaw members of substantially the same shape and size, each of said jaw members having a notch whose opposed surfaces are formed with threads, one of said jaws having a portion thereof removable, said removable portion forming one side wall of said notch, and a circular nut adapted to lie in said notches, said nut having its opposite sides provided with spiral threads adapted to cooperate with the spiral threads on the opposed walls of said notches.

3. A clamping device comprising, in combination, two opposed jaw members of substantially the same shape and size, each of said jaw members having a notch whose opposed surfaces are formed with threads, one of said jaws having a portion thereof removable, said removable portion forming one side wall of said notch, a circular nut adapted to lie in said notches, said nut having its opposite sides provided with spiral threads adapted to cooperate with the spiral threads on the opposed walls of said notches and guiding lugs on each jaw for embracing the other jaw and for guiding the same.

In testimony whereof I affix my signature.

HENRY A. RECEN.
